UNITED STATES PATENT OFFICE.

HENRY ROGERS MASSINGHAM, OF LA GRANGE, ILLINOIS, ASSIGNOR TO WESTERN ELECTRIC COMPANY, INCORPORATED, OF NEW YORK, N. Y., A CORPORATION OF NEW YORK.

STRAND DISTRIBUTOR.

Application filed December 29, 1922. Serial No. 609,637.

This invention relates to strand distributors for use in strand working machines, and more particularly to a distributor for wire twisting or stranding machines used in the manufacture of telephone cables, which are built up from twisted pairs of wires.

The object of the invention in general is to produce a strand distributor in which a maximum number of pairs of strands may be positioned within a given diameter, to furnish better access for threading the strands through the distributor in loading the stranding machine, and to prevent the breaking of the strands during the operation of the machine.

In accordance with the general features of the invention, the distributor comprises an open drum mounting, carrying a plurality of radially disposed, equally spaced pins formed in two rows, the pins in one row being staggered with respect to those in the other. This arrangement provides a maximum clearance between the strands as they are drawn through the distributor and separates the pairs from each other before they engage the angle forming member of the distributor. Mounted closely around the pins is an adjustable guard which is adapted to be moved therefrom to permit convenient access to the pins in loading the stranding machine.

Other objects and advantages of the invention will be set forth in the following description and particularly pointed out in the appended claims.

In the drawings:

Fig. 1 is a front elevation of a distributor constructed in accordance with the invention;

Fig. 2 is a vertical section thereof shown mounted on a stranding machine, and

Fig. 3 is a fragmentary plan view of Fig. 1.

Referring now to the drawings in detail, 10 represents a portion of the frame of a stranding machine, and 11 is a hollow shaft upon which the distributor is mounted. Secured to the end of the hollow shaft 11 by a plurality of screws 12 is a mounting ring 13 carrying three studs 14 spaced 120° apart. The studs 14 are each suitably secured at one end in the mounting ring 13 with the opposite end provided with a

flange 16. A drum 17 is provided having 55 an axial opening 18 through which the core of the cable being worked on is drawn. Radially disposed around the periphery of the drum, and suitably mounted therein are a plurality of hardened steel pins 19, 60 the pins 19 being formed in two rows and equally spaced, with the pins in one row set intermediate or staggered with respect to the pins in the other. Between the pins of each pair in each row are drawn two 65 pairs of twisted wire, each twisted pair being indicated by the numeral 20. The two pairs of wire between the pins of each pair of pins are spaced apart due to the staggered arrangement of the two rows of pins. 70 Mounted on the forward end of the drum 17 is a shouldered guide ring or angle forming member 21 of hardened steel provided with an axial opening having the same diameter as the axial opening 18 in 75 the drum. The guide ring 21 is secured to the drum 17 by the studs 14 which pass therethrough, the drum and guide ring being clamped against the flanges 16 on the studs by nuts 22 screw threaded onto the 80 ends of the studs.

Positioned outside of the pins 19 is a stationary guard 24 which is spaced apart from the ends of the pins a sufficient distance to prevent engagement therewith. At 85 its lower side the guard 24 is provided with a lug 25 for securing it to a support 26 slidably mounted on studs 27 suitably secured in the frame of the stranding machine. A strap 28 is secured at either end to the studs 27 which functions as a stop for the guard support when it is brought forward to its normal position as shown in full lines in the drawing. The guard is 90 locked in its normal position by thumb screws 29 threaded into the support 26. The guard is secured to the supporting member 26 by bolts passing through slots formed in the lug 25 and the support 26 at right angles to each other (Fig. 1) whereby the guard may be horizontally and vertically adjusted to facilitate installation and for mounting the guard centered with respect to the distributor pins 19.

Before threading the wires into position in loading the stranding machine, the guard 24 is first moved to the dotted line

position as shown in Fig. 2 after loosening the thumb screws 29. The wires then may be led from the supply reels (not shown) over suitable guides (not shown) and radially positioned or distributed around the distributor to give the desired arrangement of wire in the cable to be stranded.

In positioning the wires between the pins around the drum, they are merely passed over and between the ends thereof, and then led over the guide ring 21, and through a polisher 33 partially shown in Fig. 2.

After the distribution of the wires around the drum the guide 24 is moved back to its normal position to prevent the wires when the machine is in operation, from looping over the ends of the pins and becoming entangled.

Due to the staggered arrangement of the pins, which provides a maximum space between the wires, there is less likelihood of the pairs of wires becoming entangled due to any unevenness in the twist in either pair of wires. Also since the wires pass between the pins before they engage the ring 21 the pairs are more easily separated since no radially directed pressure is encountered at such a point, than if the separation were attempted as they pass over the ring where considerable radial pressure exists.

Also since all of the strands as they pass over the angle forming ring 21 are the same distance from the common axis of such ring and the polisher 33 it is evident that they will assume a frusto-conical formation and approach the polisher at uniform angles of incidence thus effectually preventing the entanglement of the strands during the air passage from the distributor to the polisher.

Further advantages of the distributor made in accordance with this invention reside in the fact that one distributor may be employed equally well for any number of pairs of strands not exceeding its capacity and broken or worn pins may be readily replaced individually without dismantling the machine.

What is claimed is:

1. A strand distributor for cable stranding machines comprising a drum secured to a rotatable member of the machine and a plurality of pins mounted in staggered relation around the periphery thereof for distributing the strands.

2. A strand distributor for cable stranding machines comprising a drum secured to a rotatable member of the machine, and a plurality of pins carried by and arranged in rows around the periphery thereof, the pins in one row being set equidistant between the pins in an adjacent row.

3. In a cable stranding machine the com-

bination with a rotatable member thereof, a strand distributor drum carried thereby, a plurality of pins mounted thereon and around the periphery thereof for distributing the strands, and a guide ring associated with said drum for spacing the strands from the periphery of said drum to reduce the friction thereof.

4. A strand distributor for strand working machines comprising a rotatable member, means carried thereby for distributing the strands and a guard for preventing the displacement of the strands during the operation of the machine, said rotatable member and guard being adjustable relative to each other.

5. A strand distributor for strand working machines comprising a rotatable member, and a plurality of pins mounted thereon for distributing the strands, and means for preventing the displacement of the strands during the operation of the machine.

6. In a cable stranding machine, the combination with a rotatable member thereof, a strand distributor carried thereby, a plurality of pins carried thereon and around the periphery for distributing the strands, and means associated therewith for preventing the displacement of the strands from therebetween during the operation of the machine.

7. In a cable stranding machine, the combination with a rotatable member thereof, a strand distributor drum carried thereby, a plurality of pins carried thereon and around the periphery for distributing the strands, and an adjustable guard for preventing the displacement of the strands from therebetween during the operation of the machine.

8. In a cable stranding machine, the combination with a rotatable member thereof, a strand distributor drum carried thereby, a plurality of pins carried thereon and around the periphery for distributing the strands, and a stationary guard adjustably positioned about the pins to prevent the displacement of the strands from therebetween during the operation of the machine.

9. A strand distributor for strand working machines comprising a rotatable member, and a plurality of projections in staggered relation thereon for distributing the strands.

10. A strand distributor for strand working machines comprising an angle forming member, a rotatable member, and a plurality of projections in staggered relation thereon for distributing the strands over the angle forming member.

In witness whereof, I hereunto subscribe my name this 20th day of December A. D., 1922.

HENRY ROGERS MASSINGHAM.
